DISPLAY RACK

Clark B. Rollins, Jr., % Nashville Display Co., 1415 Elm
Hill Pike, Nashville, Tenn. 37210

Filed Mar. 9, 1972, Ser. No. 233,396

Term of patent 7 years

Int. Cl. D6—04

U.S. Cl. D6—186

Fig. 1

Fig. 2

Fig. 3

FIG. 1 is a front perspective view of a display rack, showing my new design;

FIG. 2 is front elevational view; and

FIG. 3 is a side elevational view, taken from the right side of FIG. 2, the opposite side being substantially a mirror image thereof.

I claim:

The ornamental design for a display rack, as shown and described.
